UNITED STATES PATENT OFFICE.

FRANK S. THOMAS, OF TOPEKA, KANSAS.

KITCHEN-CABINET.

SPECIFICATION forming part of Letters Patent No. 791,512, dated June 6, 1905.

Application filed November 14, 1903. Serial No. 181,152

To all whom it may concern:

Be it known that I, FRANK S. THOMAS, a citizen of the United States, and a resident of Topeka, in the county of Shawnee and State of Kansas, have invented certain new and useful Improvements in Kitchen-Cabinets, of which the following is a specification.

The purpose of this invention is to provide a kitchen-cabinet or like article of furniture with bins or receptacles, the construction and arrangement thereof being such that the front bins are adapted to be swung on hinges, one of the sides thereof having the appearance of a door, such bins being quadrantal shaped in horizontal cross-section, the compartment into which such bin is moved also containing a sliding bin or receptacle which may be drawn forward when the swinging bin is moved to the front of the base, as will be hereinafter set forth.

In the accompanying drawings, Figure 1 is a front view of a kitchen-cabinet provided with bins made in accord with my invention. Fig. 2 is a vertical section of a portion of the cabinet, taken on the dotted line 22 of Fig. 3, showing in dotted lines the bins of one compartment projected; and Fig. 3 is a section taken horizontally through one of the compartments and the bins thereof, such section being taken on the dotted line 33 of Fig. 2.

The base A of a kitchen-cabinet made in accord with my invention is provided with open-ended compartments B B, each compartment being similar in construction, the same having parallel guide-strips a a, which are adjacent to the side walls b. The guide-strips a a serve as supports for rectangular-shaped bins C, such bins having rollers for engagement with the guide-strips a, and the bottom of such bins between the guide-strips have transverse stops c, located to depend from the bottom of the bins somewhat to the rear of the transverse center thereof, and the rear walls have upwardly-projecting portions or stops d' for engagement with the front cross-bar b' of the cabinet when the bin is drawn forward to its fullest extent. The bins C C when drawn forward assume an inclined position, as shown, and the front of the bins have handles 50 for raising and moving the same.

To the front of the compartment or com-

partments B there are hinged bins D, the same being of quadrantal shape in horizontal cross-section, and such bins are attached to the vertical sides a' a' of the base by hinges d d. 55 The side of the door opposite the hinges has a latch d'. The fronts D' of the bins D have the appearance of doors, and at right angles from the fronts project the sides D'', and at the top, as well as the bottom, there may be 60 segmental reinforcing-pieces d''. The segmental portion of the bin is preferably made of sheet metal.

By the construction shown the space rear of the front bin is utilized and the compartments are closed by the front bins. 65

Between the bins and above the same there may be drawers, and the top may be varied as to construction, though I prefer to provide the same with an upper cupboard and below 70 said cupboard with a central compartment and side drawers.

I do not wish to be limited to the particular arrangement of the drawers or top.

What I claim as new, and desire to secure 75 by Letters Patent, is—

1. In a kitchen-cabinet or similar article of furniture, a base constructed to provide a bin-receiving compartment such compartment having therein a sliding bin, and a swinging 80 bin attached to the base and adapted to be moved into the compartment and close the same when the sliding bin is positioned in the rear portion of the compartment, substantially as shown. 85

2. As an improved article of manufacture a kitchen-cabinet, comprising a base having open-ended compartments, rectangular bins which are adapted to be slid to the rear of said compartments and when drawn forward will 90 be maintained in an inclined position partially beyond the front of the base, and swinging bins hinged to the base and adapted to be swung into the compartment containing the sliding bin, substantially as shown. 95

In testimony whereof I hereunto affix my signature in the presence of two witnesses.

FRANK S. THOMAS.

Witnesses:

NELSON DYER,
C. B. WINGETT.
